UNITED STATES PATENT OFFICE

2,544,937

REFRIGERANT EVAPORATOR

Lawrence A. Philipp, Detroit, Mich., assignor to
Nash-Kelvinator Corporation, Detroit, Mich.,
a corporation of Maryland

Application July 5, 1947, Serial No. 759,157

3 Claims. (Cl. 62—126)

1

This invention relates generally to refrigerating apparatus and more particularly to refrigerant evaporators therefor.

One of the objects of the present invention is to provide a refrigerant evaporator of simplified construction to facilitate assembly of its parts and generally to reduce cost of evaporators without affecting the efficiency thereof.

Another object of the invention is to provide a refrigerant evaporator having improved heat exchange relation between a container and a refrigerant coil of the evaporator.

Another object of the invention is to provide a refrigerant evaporator having an improved arrangement of a storage container, refrigerant accumulator and a refrigerant coil to effect efficient heat absorption.

Further objects and advantages of the present invention will be apparent from the following description, reference being had to the accompanying drawings, wherein a preferred form of the present invention is clearly shown.

In the drawings:

Fig. 1 is a top plan view of my improved refrigerant evaporator;

Fig. 2 is a rear view of the refrigerant evaporator;

Fig. 3 is a view of a refrigerant system including an end view of my evaporator; and

Fig. 4 is an enlarged cross sectional view of the evaporator.

Referring to the drawings by characters of reference, the numeral 20 designates generally, a refrigerant evaporator for use in a domestic or household type of refrigerator. The evaporator 20 comprises, in general, a storage container 22, a container closure or cap 24, a refrigerant coil 26 and a refrigerant accumulator 28. As shown, I wrap the refrigerant coil 26 around the body of the container 22 and mount the accumulator 28, connected to the coil, on the cap 24.

The container 22 is preferably made of sheet steel, bent to form a box-like structure having a bottom wall 30, top wall 32 and side walls 34. As shown, the cap 24 is fitted snugly over one end of the container body, forming the rear wall of the container. The cap 24 and the container body may be welded or be otherwise suitably secured together. The front of the evaporator container 22 is open to provide access to the interior thereof wherein ice trays and foods (not shown) may be stored. An outturned flange 38 surrounds the container access opening to give a finished appearance thereto; the flange 38 preferably being

2

formed out of the sheet metal of the container body to increase rigidity of the container.

Extending around the evaporator container 22, the refrigerant flow coil 26 may be held against the outer surfaces of the container bottom wall 30, top wall 32 and side walls 34 by spaced U-clips 40. These clips 40 may be spot welded or be otherwise suitably secured to the walls of the evaporator container to hold the coil 26 in good heat exchange relationship therewith. In order to insure efficient heat absorption from the container walls by the refrigerant passing through coil 26, I provide a container engaging, flat portion 42 on the coil longitudinally thereof to increase surface area contact between the coil and the walls of the container (see Fig. 4). In contact with a side of the refrigerant coil on the top of the container 22 is an end portion or bulb 44 of a thermostat (not shown). The coil 26 and thermostat bulb 44 are attached together and to the top wall 32 of the evaporator container by a pair of metal clips 45 which may be welded to the container 22 adjacent the container cap 24.

The accumulator 28 is a metal conduit of U-shape having a loop portion from which legs extend in diverging relationship to each other. This U-shaped accumulator 28 is held against the outer surface of the cap 24 by metal clips 46 which may be welded to the cap 24. Starting from adjacent one side of the evaporator container 22, the accumulator or conduit 28 extends from its inlet end, as at 48, across the cap upwardly, at a slight angle to the horizontal, to the loop portion of the accumulator and then extends back across the cap at a slight angle upwardly, terminating at an outlet, designated by the numeral 50.

The refrigerant system may include a refrigerant motor-compressor unit 52 and a refrigerant condenser 54. A capillary tube 56 supplies refrigerant from the condenser 54 to the inlet or upper end of the evaporator coil 26 which is located on the top wall 32 of the evaporator container. Refrigerant passes through the coil 26, absorbing heat from the walls of the evaporator container 22 and then passes into the lower end of the accumulator 28, absorbing heat from the cap or rear wall of the evaporator. Gaseous refrigerant is withdrawn from the upper end of the accumulator 28 by the motor-compressor unit to which the gaseous refrigerant returns through conduit 60. As shown in Fig. 3, a portion 62 of the return conduit 60 is preferably arranged in contact with the capillary tube 56 to cool liquid refrigerant.

From the foregoing description, it will be noted that I have provided an improved evaporator of simplified, inexpensive construction in which a container proper has a coil wound therearound and a rear container cap carries a refrigerant accumulator. Also, I have provided an improved evaporator of the above mentioned character having enlarged surface contact between the refrigerant coil and walls of the container.

Although only a preferred form of the invention has been illustrated, and that form described in detail, it will be apparent to those skilled in the art that various modifications may be made therein without departing from the spirit of the invention or from the scope of the appended claims.

I claim:

1. A refrigerant evaporator comprising, sheet material forming top, bottom and sides of a container, a refrigerant passage in heat exchange relation with said sheet material, a closure member fitting over said top, bottom and sides forming the rear wall of the container, and a refrigerant accumulator carried by said closure member connected to said refrigerant passage.

2. A refrigerant evaporator comprising, sheet metal material forming top, bottom and sides of a container, a cap closing the rear of the container, a refrigerant coil wrapped around said container in contact with the outer surface thereof having an end portion bent around one end of said container, and a conduit secured to the outer

surface of said cap forming a refrigerant accumulator connected to said refrigerant coil bent end portion.

3. In a refrigerant evaporator a supporting member having a rear wall, refrigerant flow passages in heat exchange relationship with said supporting member, a conduit forming an accumulator attached to said rear wall, said conduit being U-shaped with its legs diverging from the loop of the U at acute and opposite angles to the horizontal and being arranged in engagement with said rear wall, and means attaching one of said legs to said refrigerant flow passage.
